WIRE COVERING MACHINE

Magloire Brodeur, Providence, R. I., assignor of
one-half to Eleuterio Mollicone, Johnston,
R. I.

Application January 10, 1941, Serial No. 373,986

4 Claims.

(Cl. 57—15)

This invention relates to a wire covering machine, and more particularly to mechanism for winding wire with filamentary material in superposed layers for wear resistant or insulating purposes.

One object of the invention is the provision in a device of this character of a mechanism which comprises supporting frames adapted for adjustment relative to each other, carrying respectively winding and after treating means for laying filaments upon the wire and after treating the same to form a compact and cohesive covering.

Another object of the invention is the provision of means for laying a plurality of filaments spirally about a wire in generally superposed relation with each other during a single winding operation.

A further object of the invention is the provision of a mechanism of the character described provided with wire winding and after treating means arranged for successive operation to suitably apply filaments to the surface of the wire and subject the wire and filaments to appropriate after treatment for retaining the filaments in their wire covering positions and incorporate them into a unitary structure.

Other objects and advantages of the invention relate to various improved details of construction and novel arrangements of the parts as will be more fully set forth in the detailed description to follow.

Referring to the drawings:

Fig. 1 is a side elevational view of the mechanism,

Fig. 2 is a top plan view of the same,

Fig. 3 is a vertical sectional view, taken substantially along the line 3—3 of Fig. 1, showing a portion of the mechanism in elevation,

Fig. 4 is a vertical sectional view, taken substantially along the line 4—4 of Fig. 3,

Fig. 5 is a detail sectional view, taken substantially along the line 5—5 of Fig. 2, and showing the manner of operating the traversing mechanism for winding the finished wire on the spool, and

Fig. 6 is a detail plan view of the drawing roll and winding spool, showing the manner of driving the spool from the drawing roll.

In the embodiment of the invention illustrated herein, 1 designates generally a supporting frame which may be of any suitable or desired character and may comprise a base 2 provided with spaced upright standards 3 mounted thereon and a tubular guide member 4 carried by the

base and secured in fixed position thereon by means of a clamping sleeve 5. Spaced arms 6 carried by the base are adapted to support a reel 8 carrying the wide to be treated, and a guide member 9 is provided for guiding the wire 10 from the reel 8 to an opening 11 formed in the tubular guide member 4, in order that the wire may pass upwardly in the guide member 4 and through a restricted opening formed in 10 a guide plate 12 positioned within the tubular member 4 at a point adjacent to the upper end thereof for maintaining the wire 10 in a relatively fixed position as it passes upwardly from the tubular member 4.

15 A table 14 is mounted for rotation about the tubular member 4, being supported for rotation on the tubular member by means of supporting plates 15 which may be secured to the tubular member 4 in any suitable or desired manner to provide bearings for the table 14. The table 14 supports a plurality of thread carriers 16 and a corresponding number of thread guides 17 for guiding threads or filaments 18 from the carriers to the wire 10. Each thread guide 17 20 may comprise a fixed section 19 and a movable section 20 adjustably connected with each other and adapted to be secured together in vertically adjusted positions by means of suitable clamping connections 21.

25 The table 14 is provided with an edge groove 22 to receive a driving belt 23 driven from a pulley 24 carried by the shaft 25 of a motor 26. The motor 26 may be secured to and supported by the auxiliary frame 28 through connections

30 29, as shown herein, or may be carried by separate supporting means mounted upon the base 2 if desired. When the motor is supported from the auxiliary frame 28, as shown herein, the lower portion of the motor shaft 25 may be mounted for rotation and longitudinal sliding movement in a bearing sleeve 30 carried by or suitably supported from the base 2, in order to permit operation of the mechanism in different

35 vertically adjusted positions of the motor 26 relative to the base 2. It will be understood that the pulley 24 carried by the shaft 25 is adapted to be fixedly secured to the shaft in any one of a plurality of vertically adjusted 40 positions, in order to position the same in driving relation with the table 14 in different vertically adjusted positions of the motor 26. In this way, vertical adjustment of the auxiliary frame 28 may be had while permitting rotation of the table 14 from the shaft 25 through the pulley

45 50 55

24 and drive belt 23 in all vertical positions of the motor 26.

The auxiliary frame 28 is mounted for vertical adjustment on the standards 3, and is held in any one of a plurality of adjusted positions thereon by nuts 34. While two spaced standards 3 are shown herein as supporting the auxiliary frame 28, additional supporting standards may be employed for this purpose as may be found desirable, and such additional standards may be arranged in pairs and provided with nuts or other holding means for supporting the auxiliary frame in various adjusted positions relative to the base.

The auxiliary frame 28 may comprise a transverse frame member 35 receiving the upper end portions of the standards 3 and a rearwardly extending frame portion 36 forming a receptacle 37 having a cover 38 and adapted to receive wax or other coating or impregnating material as indicated at 39, in a liquid or semi-liquid state suitable for impregnating or coating the filamentary material to increase the insulating or wear resistant qualities of the covering. A pair of transverse rods or rolls 40 are carried by the portion 36 of the auxiliary frame and located within the receptacle 37, being positioned below the surface of the liquid 39 therein to guide the wire 10 below the surface of the liquid after the application of the filaments to the wire.

A second tubular guide member 42 is adjustably mounted in the transverse frame member 35 and a set-screw 43 is provided for holding the tubular guide member 42 in any one of a plurality of vertically adjusted positions in the frame member, depending upon the vertical positioning of the auxiliary frame 28 with respect to the base 2 and the desired spacing of the guide member 42 from the guide member 4 for applying the filaments to the wire. A guide plate 44, having a restricted guide opening formed therein is positioned within the lower end of the tubular guide member 42 to co-operate with the guide plate 12 for maintaining the wire 10 in a definitely fixed location as it receives the filaments from the carriers 16.

Vertical standards 45 are carried by the frame 28 to support rotatably a guide pulley 46 for guiding the wire 10 as it passes from the tubular guide member 42, and similar standards 47 support a drawing roll 48 for carrying the treated wire after its passage under the guide rolls 40 and through the after treating bath in the receptacle 37.

The drawing roll 48 not only supports the wire but carries a multiplicity of turns of the treated wire, which may be of a number sufficient to extend nearly the length of the roll 48. The roll 48 is provided at one end with a drive pulley 50 carrying a drive belt 51 by which the roll 48 may be driven at a constant speed from the motor shaft 25. The opposite end of the roll 48 is provided with a drive pulley 52 for driving a spool 54 on which the finished wire is to be wound.

Rearwardly extending arms 55 support a spool 54 for receiving the wire after it leaves the roll 48, the spool 54 being driven from the pulley 52 through a drive belt 53 and pulley 56 carried by the spool shaft 57. Resilient driving means (not shown) may be employed between the spool 54 and the drive pulley 52 carried by the drawing roll, together with any suitable slip connection for obtaining the necessary variation in axis speed of the spool 54 as the wire is wound on

the spool, without exerting a pull on the drawing roll or otherwise interfering with its operation.

For driving the drawing roll 48 from the shaft 25, as well as the wire traversing mechanism, a pulley 60 is carried by that portion of the motor shaft 25 located upon the opposite side of the motor 26 from that to which the pulley 24 is secured, and a belt 61 operatively connects the pulley 60 with a pulley 62 carried by an idler shaft 63 supported rotatably in one or more bearings 64 carried by a portion of the auxiliary frame 28. The idler shaft is provided with a pulley 65 for driving the drawing roll 48 through the belt 61 and also carries a cam 67 engaging a yoke 68 formed in one end of a lever 70, the lever 70 being pivotally supported, as at 71, from a portion of the auxiliary frame 28. The opposite end of the lever 70 is pivotally connected, as at 72, with a link 73 for oscillating a traversing guide arm 74 which is supported by the auxiliary frame 28, as at 75, and provided with guide means 76 for laying the wire 10 upon the spool 54.

In the operation of the mechanism above described, the wire 10 from the spool 8 is drawn over the guide pulley 9 into the opening 11 of the tubular member 4 and upwardly through the restricted opening in the guide plate 12 from which it passes through the restricted opening in the guide plate 44 and upwardly through the tubular guide member 42 to pass over the guide pulley 46. From that point the wire 10 is passed downwardly into the receptacle 37 and under the rolls 40, and then upwardly over the drawing roll 48 and then through the guide means 76 carried by the traversing guide arm 74 for laying it upon the spool 54 as the spool is rotated through its driving connections from the drawing rolls 48.

In passing from the guide block 12 to the guide block 44 a plurality of strands or filaments 18 are applied to the surface of the wire 10 in the form of spiral windings, which are preferably applied in superposed layers through the different heights of the guides 17. That is, it may be found desirable to employ filaments of different materials for the different layers of spiral windings, as, for example, the first winding to be applied to the wire may consist of a rubber thread taken from one of the carriers 16 and passed through the lowest of the several guides 17, the next filament to be applied may be a silk thread from one of the carriers 16 passed through the next highest of the guides 17. The remaining threads or filaments to be applied, whether one or more in number, may be of cotton, jute or other fibrous material, or even of the same material as that of the second filament applied, are taken from the remaining carrier or carriers employed and passed through a guide or guides 17 of progressively greater height than those previously mentioned in such a manner that each successive thread or filament is directed into contact with the wire at a point above the thread next adjacent thereto. In this way, each thread or filament is applied as a separate spiral winding to form a surface covering of substantially uniform diameter throughout its extent. By reason of their different points of application each thread or filament is applied independently of the others, since those applied at the lower heights from the surface of the table 14 are complete in their spiral application before those applied from higher points are formed on the upwardly moving wire.

Thus, for example, the rubber thread mentioned as first applied, forms a spiral layer di-

rectly on the wire, the silk thread next applied forms a spiral winding over the previously applied rubber thread, and the cotton, or other threads, in one or more layers are each superposed on the layer last before applied. In this way, a plurality of spiral windings may be built up as superposed layers on the wire, each of the later applications tending to assist in holding the initial layers firmly in position on the wire.

After the application of the various layers of wound material, the wire 10 passes upwardly through the tubular guide member 42 and over the pulley 46, then down through the receptacle 37 where the layers of applied material are subjected to impregnation or partial impregnation by wax or other binding material 39 contained in the receptacle.

The application of this material to the spirally wound wire tends to compact and amalgamate the coverings, and by the use of a binder of a suitable character, not only binds the applied layers together, but may increase substantially the insulating qualities of the applied coating.

Through operation of the mechanism above described a definite and substantially fixed quality of the wire coating may be obtained, wherein the coating may comprise layers of different materials superposed one upon the other in any desired order of radial arrangement, and wherein the materials applied may possess different wear resistant and insulating qualities but so arranged in the order of their application as to best protect the wire from abrasion and at the same time give it maximum insulation.

In driving the winding spool 54 from the drawing roll 48 a tension means of a suitable character may be positioned between the drawing roll 48 and the spool 54 to apply such tension to the wire as may be desirable for laying it evenly on the surface of the spool, which tension means may be suitably positioned on the guide arm 74, such as by association with the guide means 76.

While I have shown the several parts as driven by pulleys and connecting belts for operating the mechanism, it will be understood that suitable gears and gear trains may be substituted therefor with such suitable shaft connections as may be desired for operatively interconnecting the operating parts for driving the same from the motor or other power source.

What I claim is:

1. A mechanism for applying a filamentary covering to a wire comprising separate supporting frames, means adjustably connecting said supporting frames for securing them in any one of a plurality of adjusted positions relative to each other longitudinally of the path of travel of the wire, opposed guide members each carried by one of said frames for guiding the wire, filament supporting means carried by one of said frames provided with a plurality of filament carriers and mounted for movement about the path of travel of the wire, guide means carried by said filament supporting means and located each in inwardly spaced relation with a carrier radially of the filament support for guiding a plurality of filaments into position for application to the wire in spaced positions longitudinally of the wire, means carried by the other of said frames for drawing the wire through said opposed guide members, and means for driving said wire drawing means and filament supporting means in substantial synchronism comprising a single drive shaft provided with power transmitting

members adjustable relative to each other longitudinally of the shaft for operating said wire drawing and filament supporting means.

2. A wire covering mechanism comprising a fixed tubular guide member and a movable tubular guide member, said members being located in spaced axially aligned relation with each other and having wire receiving openings of a size only slightly in excess of the diameter of the wire, means for securing said movable guide member in any one of a plurality of adjusted positions relative to said fixed tubular guide member while retaining the guide members in axial alignment, a filament support rotatably carried by said fixed guide member, filament carriers mounted upon said filament support, separate adjustable guides for said filaments mounted on said filament support and having their several guide portions located at varying distances from the plane of rotation of the filament support to direct the separate filaments into contact with the wire at points spaced from each other longitudinally of the wire, and means for rotating said filament support and drawing the wire through said guide members simultaneously and in substantially synchronized relation.

3. A wire covering mechanism comprising tubular guide members located in axially aligned relation with each other, one of said guide members being stationary and the other guide member being mounted for axial adjustment toward and from said stationary guide member, wire guiding means carried by said tubular guide members and having restricted openings for receiving the wire to hold the same in fixed line position during its movement between said guide members, a filament support mounted upon said stationary guide member for rotation about said guide member as a center, filament carriers rotatably mounted upon said support, longitudinally adjustable filament guides carried by said support and mounted to project outwardly from the plane of rotation of the support, said filament guides having the guide portions thereof terminating at varying distances from the plane of rotation of the support to direct the different filaments into engagement with the wire at points spaced from each other longitudinally of the wire, means for rotating said filament support, and means for imparting travel to the wire in substantially timed relation with the movement of said filament support.

4. A wire covering mechanism comprising a base, a tubular upright wire guiding member carried by the base, a filament support rotatably mounted upon said wire guiding member, filament carriers rotatably mounted on said filament support, frame supporting means carried by the base, a frame mounted upon said supporting means and provided with a tubular guide member located in axially aligned relation with said first named guide member, means for securing said frame in any one of a plurality of vertically adjusted positions relative to said base, means securing said last named tubular guide member in any one of a plurality of vertically adjusted positions relative to said first named tubular guide member, a wire drawing roll carried by said frame, and means for driving said roll and rotating said filament support simultaneously and in substantial synchronism in any one of a variety of vertically adjusted positions of said frame relative to said base.

MAGLOIRE BRODEUR.
